UNITED STATES PATENT OFFICE

LYLE D. GRUBBS, OF HINSDALE, ILLINOIS

DESIGN FOR A BIRD FIGURE

Application filed September 26, 1932. Serial No. 45,070. Term of patent 3½ years.

To all whom it may concern:

Be it known that I, LYLE D. GRUBBS, a citizen of the United States, residing at Hinsdale, in the county of DuPage, and State of Illinois, have invented a new, original, and ornamental Design for Bird Figure, of which the following is a specification, reference being had to the accompanying drawing, forming part thereof.

I claim:—

The ornamental design for a bird figure, as shown.

In witness whereof, I hereunto subscribe my name this 23 day of September, 1932.

LYLE D. GRUBBS.
